UNITED STATES PATENT OFFICE.

HARRY MILLWARD, OF BIRMINGHAM, ENGLAND.

ACETYLENE-GAS LAMP.

SPECIFICATION forming part of Letters Patent No. 623,412, dated April 18, 1899.

Application filed October 22, 1898. Serial No. 694,295. (No model.)

To all whom it may concern:

Be it known that I, HARRY MILLWARD, metal-spinner, a subject of the Queen of Great Britain, residing at Mary street, St. Pauls, 5 Birmingham, in the county of Warwick, England, have invented certain new and useful Improvements in Acetylene-Lamps, of which the following is a specification.

This invention is an improved lamp for generating and burning acetylene gas and is of special importance in connection with a cycle-lamp. The said improved lamp is designed upon that system of generation in which the water drops upon the carbid and is 15 constructed so that its dimensions are small, its appearance neat, and its working effective and sure. Its general construction is such as to generate only the amount of gas requisite and to thoroughly dry the same before 20 being burned, this latter in order to prevent the carbonization of the burner.

The said invention will be described herein in connection with the annexed sheets of drawings, in which is shown a lamp suitable 25 for use on a cycle.

In the said sheets a longitudinal vertical section of a complete lamp is shown in Figure 1; a horizontal section in Fig. 2 through the lamp's body part, but with a portion of 30 the fore part of the lamp broken away; in Fig. 3 a transverse vertical section of Fig. 1 on the dotted line F; and in Figs. 4 and 5 parts of the lamp, as shown in Fig. 1, separated or detached.

In the said figures the body part *a* of the lamp, which may be of any suitable horizontal section giving a hollowed-out middle, but which is preferably crescent-shaped, as shown by Fig. 2, is built up of an inner and outer 40 metallic shell *a*² *a*³, connected and distanced at top and bottom by walls *a*⁵ *a*⁴, so as to leave a space between them to constitute a chamber or holder *c* for the storage of the water or other liquid used in the generation of 45 the gas, the said chamber *c* being formed by a hollow construction of the lamp's body. This water-chamber is provided with an inlet *c*² for filling and with a regulating valve or cock *c*³ for the purpose of withdrawing water 50 therefrom, the last named taking the form of a screw-pin *d*, having a coned end *d*² and

a small outlet-hole *d*³ within the bottom of the chamber *c*, and which said hole is open to the interior, the said coned end *d*² acting in conjunction with the outlet-hole *d*³ for 55 turning on and shutting off the supply of water to the carbid.

The lamp-body *a* is of such a shape as to form a recess, hollowing, or setback part *e*² central to the water-chamber *c* for the purpose of allowing a part of the bell *e* to locate itself therein and nestle within the lamp's body as close as possible. The said bell is fitted with a glazed front *e*³, a cowl *e*⁴, and a reflector *e*⁵ and is hinged to the fore part of 65 the base of the lamp's body at *e*⁶, so that it can be thrown forward clear of the burner by unscrewing a connection *e*⁷. The said burner (marked *f*) is arranged to project from the base of the lamp's body into the interior of 70 the bell *e* and is in communication with the gas-generating chamber, which will be hereinafter fully described. A suitable connection means *f*² is fitted to the back of the lamp's body for the lamp's connection to the 75 head of a cycle.

Formed upon the under side of the base of the lamp's body *a* is a central boss or cylindrical part *g* and a ring-recess *g*², the last-named surrounding the former. This boss 80 has a small hole *h* within its end, which is in communication with the burner *f* of the lamp through the space inclosed by the boss *g* and thence through the burner-tube *f*, which opens into the top of said space, as shown in 85 Fig. 1. Through the center of the space inclosed by said boss *g* passes a water-supply tube *m*, leading from the regulating valve or cock *c*³. From said cock *c*³ the tube extends with a slight downward inclination to the 90 center of the space inclosed by the boss *g*, where it takes a vertical direction and passes through the bottom of the boss *g* and extends downward into the generating-chamber. The said boss *g* is preferably of a hollow construction, as shown. The recess *g*² has within its bottom a flexible ring *n* for making good the joint of the lamp's body with the gas-generating chamber. The last named forms the 95 actual base of the lamp and takes the form 100 of a barrel or cylinder *o*, in which the carbid for making the gas is placed. The crown of

this generating-chamber o is formed with a boss o^2 and a shallow socket o^3 , the first named surrounding the latter, the said shallow socket to form a gas-drying chamber and 5 to fit over the boss g on the lamp-body and the boss o^2 to engage in the recess g^2 and to rest upon the flexible material n , therefore making good the joint between the lamp-body and the generating-chamber. Centrally 10 within the shallow socket o^3 and projecting through its nearly-closed bottom (which has a hole o^4 within it for the passage of the gas from the generating-chamber to the said socket) is arranged an inverted-T-shaped 15 tube s , which is fixed to and within the said generating-chamber by a screwed collar s^2 or by soldering. The shank s' of this inverted-T-shaped tube is adapted, when the base proper is connected to the lamp-body, to fit 20 sheath-like over the depending end of the tube m and the head part s^3 of the said tube to extend longitudinally within the generating-chamber o for the greater part of the chamber's length. This head part s^3 has a 25 number of perforations s^4 within it and is entirely covered with a material s^5 —such as cotton, wool, fiber, or sponge—it being only through this latter that the contact of the water with the carbid is made. The one end 30 of the generating-chamber o is closed by a removable cap u , while the other end u^2 is a fixture.

The shallow socket o^3 is filled with a gas-drying material o^5 , and all gas leaving the 35 generating-chamber by the small hole o^4 must, before passing to the burner f by way of the hole h , pass through said drying material o^5 . The gas-tight connection, which is made between the generating-chamber and the lamp-body by the parts g, g^2, o, o^2 , and n , is by reason of the parts being pulled together with the part n between them, this being accomplished preferably by an inclined bayonet-slot connection. Any other familiar construction 45 that will accomplish the result aimed at may be used in place of that shown. A water-tight joint is made between the tube s and the tube m through a yielding washer w , which prevents any water from the chamber c getting 50 to the gas-drying material o^5 if the lamp is at any time inverted.

The water from the chamber c reaches the carbid in the generating-chamber by way of the regulating-valve c^3 , the tube m , the inverted-T-shaped tube s , the holes s^4 , and the wrapping s^5 , the slight pitching of the horizontal part of the first-named tube insuring all the water passed through the valve instantly finding its way into the tube s , so that 55 60 when the cock c^3 is shut there is no surplus of water left in the tubes m or s . The gas generated leaves the chamber o and passes to the burner f by way of the hole o^4 , the drying material o^5 , and the hole h , the said holes being arranged on opposite sides of the lamp's center, which insures the gas taking a circuitous course through the drying material. 65

If necessary, the hollow interior of the boss g may contain gas-drying material, as a dry gas is very important to prevent the burner 70 carbonizing.

Having now described my invention, what I claim, and desire to secure by Letters Patent, is—

1. In an acetylene-lamp the combination of 75 a lamp-body part carrying a burner and whose base or lower extremity is fitted with a ring-recess g^2 and a cylindrical part having a gas-way h through it an attachable generating-chamber o whose outer surface is formed with 80 a boss o^2 and a socket o^3 to engage the parts $g^2 g$ the said socket o^3 having a hole o^4 within it which communicates with the generating-chamber and the gasway and a flexible ring n which comes between the parts g, g^2 and 85 $o^2 o^3$ when they engage to make gas-tight the joint between the body part of the lamp and the generating-chamber, substantially as described.

2. In an acetylene-lamp the combination of 90 a lamp-body part carrying a burner and whose base or lower extremity is provided with a boss g and ring-recess g^2 the boss having a gas-aperture h , and an attachable generating-chamber o whose outer surface is formed with 95 a chamber containing gas-drying material which is in communication with the generating-chamber and whose outer surface is formed with parts $o^2 o^3$ for the engagement with the parts $g^2 g$ on the base of the body 100 substantially as described.

3. In an acetylene-lamp the combination of 105 a lamp-body part a formed into a water-chamber c and with a central recessed part e^2 and which also carries a burner f a bell e fitted with a lens and reflector which is adapted to seat a part of itself within the recessed part e^2 , a regulating valve or cock c^3 fitted to the water-chamber c and which has a water-tube m with an inclined horizontal part leading to 110 a vertical part leading therefrom, a horizontal-extending attachable barrel or cylinder o forming the generating-chamber and which is adapted to be connected to the lamp's body so as to form its base proper, and an inverted-T-shaped tube s carried by and located within the cylinder o , the shank of said tube s being fitted over the vertical portion of the tube m and its perforated head arranged lengthwise in the generating-chamber, said perforated portion being wrapped with a suitable material, substantially as described. 115

4. In an acetylene-lamp the combination of 120 a lamp-body part a forming a water-chamber c and fitted with a regulating valve or cock c^3 and a burner f a water-tube m fitted to the base of the body part a so as to lead from the valve or cock c^3 to the lamp-body's base and an attachable horizontally-extending generating-chamber o fitted with an inverted-T-shaped tube s and a gas-outlet hole o^4 which is in communication with the burner f substantially as described. 125

5. In an acetylene-lamp the combination of

a lamp-body part *a* formed with parts *c* and *e*² and fitted with a hinged bell *e* a regulating valve or cock *c*³ a burner *f* a ring-recess *g*² a cylindrical part *g* a flexible ring *n* and a gas-way *h* a water-tube *m* leading from the valve *c*³ to the center of the bottom of the lamp-body and which has a washer *w* upon it and an attachable horizontally-extending generating-chamber *o* fitted with an inverted-T-shaped perforated but wrapped tube *s* and

having parts *o*² *o*³ and *o*⁴ formed upon its exterior substantially as described.

In testimony whereof I have signed my name to this specification in the presence of two subscribing witnesses.

HARRY MILLWARD.
